(57) **CLAIM**

I claim the ornamental design for a golf tool accessory device, as shown and described.

DESCRIPTION

FIG. 1 is a front perspective view of the golf tool accessory device;

FIG. 2 is a rear perspective view of the golf tool accessory device;

FIG. 3 is a top view of the golf tool accessory device;

FIG. 4 is a side elevational view of the golf tool accessory device;

FIG. 5 is a front elevational view of the golf tool accessory device;

FIG. 6 is a side elevational view of the opposed side of the golf tool accessory device;

FIG. 7 is a bottom view of the golf tool accessory device;

FIG. 8 is a rear elevational view of the golf tool accessory device;

FIG. 9 is a front perspective view of the golf tool accessory device with the divot tool removed, and the ball spot slug removed in an exploded view; and,

FIG. 10 is a rear exploded perspective view of the golf tool accessory device.

The broken line showing on the device and the backside of the golf tool is included for the purpose of illustrating and forms no part of the claimed design.
